REFRIGERATOR

Harry C. Shagaloff, Evansville, Ind., assignor to
 Servel, Inc., New York, N. Y., a corporation of
 Delaware

Application December 26, 1940, Serial No. 371,626

11 Claims. (Cl. 62—1)

This invention relates to refrigerators in which the refrigerating apparatus is operated by heat from a liquid fuel burner, and it is an object of the invention to provide a simply and quickly operated disconnect in the flame path between a refrigerating apparatus and its burner so that the latter is readily movable and removable for servicing, as set forth in the following description with reference to the accompanying drawing, wherein:

Fig. 1 shows partly in elevation and partly in section a portion only of a refrigerator embodying the invention;

Fig. 2 is a view like that of Fig. 1, showing a different operative relation of parts;

Fig. 3 is a detail section taken on line 3—3 in Fig. 1; and

Fig. 4 shows alone and in elevation the movable part of the disconnect.

Referring to the drawing, a refrigerator cabinet 10 is equipped with an absorption type refrigerating apparatus of which there is shown only the lower end of a generator 11. A flue 13 for heating the generator 11 projects downward beyond the lower end of the generator. The generator is encased in suitable thermal insulation secured by a casing 12.

Below the generator 11 is a fuel tank 14 having therein a suitable liquid fuel, such as kerosene. Mounted on the tank is a burner 15 having a wick 16 depending into the tank. The burner is secured on the tank 14 by means of brackets 17. The burner is provided with a stub chimney 18 of glass or other suitable material. The tank and burner are movable as a unit so as to be withdrawn from beneath the generator for servicing.

To obtain good heating efficiency, it is desirable that the chimney and flue be made, in effect, an integral part of the flame system, that is, that the chimney 18 be connected in aligned sealed relation with the flue 13. For this purpose I provide a self-sealing disconnect in the form of a ring or sleeve 19 of metal or other suitable heat resisting material with a central opening 20 and which is slidably and rotatably journalled on the lower projecting end of the flue 13. The bottom or base 21 of the ring is formed with an annular recess 22 adapted to rest upon and engage the top of the chimney 18, and within the recessed area the surface of the base is flat and smooth to effect a seal with the top of the chimney.

Above the base, the ring is enlarged in diameter to provide a flange 23. The under surface of flange 23 is formed with a series of inclined

faces or cams 24. The ring 19 is rotatably supported from the generator insulation casing 12 by means of brackets 25 which engage beneath the inclined faces or cams 24 of the ring. To facilitate rotation of the ring the latter is provided with a suitable handle 27.

Fig. 2 shows the ring 19 in chimney and flue connecting and sealing position. In this position the bottom of the ring 19 rests on the top of the chimney 18, there being a slight clearance between the inturned portions 26 of the brackets 25 so that the ring rests by gravity directly on the top of the chimney. To disconnect the chimney from the flue, it is only necessary to push the handle 27 to the position shown in Fig. 1, thereby bringing the cam faces 24 in contact with the inturned portions 26 of the brackets 25 and causing the ring to move upward to the position shown in Fig. 1. To again connect the chimney and flue in aligned and sealed relation after the burner has been returned to position beneath the flue 13, the handle 27 is turned back to its original position, whereupon the ring 19 descends and rests by gravity upon the top of the chimney.

When the seal ring 19 is down, it rests on top of the chimney and seals by gravity. Extra pressure cannot be exerted on the glass chimney due to further rotation of ring 19 since once contact is made between the ring and chimney, further rotation simply breaks contact between the members 26 of the brackets 25 and the cam faces of the ring. This feature results in uniformity of seal, since it depends on the weight of the ring, the flatness of the lower face of the ring and the top of the chimney, all of which factors are easily controlled.

While I have shown and described a specific embodiment of my invention, it is to be understood that this has been done for the purpose of illustration only, and that the scope is not to be limited thereby, but is to be determined from the following claims.

What is claimed is:

1. In a refrigerator having a heat-receiving element provided with a flue, a burner including a chimney removably mounted in an operative position beneath said element with an end of said chimney contiguous to an end of said flue, and a member coacting with said flue and chimney and movable independently of movement of said burner or chimney to and from a position sealing the joint between the contiguous ends of said flue and chimney when in said operative position.
2. In a refrigerator having a heat-receiving element provided with a flue, a burner including

a chimney removably mounted beneath said element with said chimney substantially in alignment with said flue, a member supported for movement independent of movement of said burner or chimney and substantially axially of the flue and chimney, said member having a portion in movable engagement with the lower end of the flue and another portion adapted to engage the top of the chimney and effect a seal between the contiguous ends of the flue and chimney.

3. In a refrigerator having a heat-receiving element provided with a flue, a burner including a chimney removably mounted beneath said element with said chimney communicating with said flue, a member in movable engagement with the lower end of the flue, means for imparting to said member reciprocating movement independent of movement of said burner and substantially axially of the flue, said member having a part adapted to rest on the top of the chimney and effect a seal between the contiguous ends of the flue and chimney.

4. In a refrigerator having a heat-receiving element provided with a flue, a burner including a chimney removably mounted beneath said element with said chimney communicating with said flue, a member encircling the lower end of the flue, means for imparting to said member reciprocating movement independent of movement of said burner and substantially axially of the flue, said member having a part adapted to rest on the top of said chimney and effect a seal between the contiguous ends of the flue and chimney.

5. In a refrigerator having a heat-receiving element provided with a flue, a burner including a chimney removably mounted beneath said element with said chimney communicating with said flue, a member in movable engagement with the lower end of the flue and having a part with a surface adapted to rest on the top of the chimney, means rotatably supporting said member including cam means operative upon rotation of said member to lower the latter onto said chimney.

6. In a refrigerator having a heat receiving element provided with a flue, a burner including a chimney removably mounted beneath said element with said chimney communicating with said flue, a member encircling the lower end of the flue and having a lower surface adapted to rest on the top of the chimney and effect a seal between the chimney and flue, said member being provided with cam surfaces, and means rotatably supporting said member and having portions so engaging said cam surfaces that when said member is rotated it is moved axially of the flue into and from sealing position.

7. In absorption type refrigerating apparatus including a generator having a flue and a burner provided with a chimney removably mounted be-

neath the generator with the chimney communicating with the flue, a member in movable engagement with the lower end of the flue and having a portion adapted to rest on top of the chimney, means rotatably mounting said member for movement axially of the flue including cam means whereby when said member is rotated it is lowered onto said chimney, said means being operative to free said member when the latter rests on said chimney.

8. In a refrigerator having a heat-receiving element provided with a flue, a burner including a chimney removably mounted in an operative position beneath said element with said chimney communicating with said flue, a member movable relative to both said flue and chimney when in said operative position and having a portion in movable engagement with one of said flue and chimney and engageable with the other of said flue and chimney to provide a closed flame path therebetween.

9. In a refrigerator having a heat-receiving element provided with a flue, a movable fuel tank, a burner rigidly mounted on said tank and having a chimney communicating with said flue, a member in movable engagement with the lower end of the flue and having a portion adapted to engage the chimney and provide a closed flame path between the flue and chimney, and means supporting said member operative to permit gravity movement of the latter into engagement with said chimney.

10. In a heat operated refrigeration apparatus having a heat receiving part provided with an upright flue, a liquid fuel burner having a chimney, said burner being movable horizontally into and away from a position in which said chimney is in substantial alignment with said flue, a sleeve slidably engaging the lower end of said flue, and means for raising and lowering said sleeve, the lower part of said sleeve being adapted to rest upon said chimney substantially in air tight relation therewith, and said means being operative to release said sleeve so that the latter rests under its own weight when lowered upon said chimney.

11. In heat operated refrigeration apparatus having a heat receiving part provided with an upright flue, a liquid fuel burner having a glass chimney, said burner being horizontally movable into and away from a position in which said chimney is in substantial alignment with the lower end of said flue, a ring slidably and rotatably journaled on the lower end of said flue, a handle for turning said ring, and cam means operative upon turning of said ring to raise said ring against gravity and permit said ring to descend due to gravity, the lower part of said ring being adapted to rest upon and snugly engage the upper end of said chimney.
